UNITED STATES PATENT OFFICE.

CHARLES A. ROBERTSON, OF SPRINGFIELD, ILLINOIS, ASSIGNOR TO MONTGOMERY WARD & CO., INC., OF CHICAGO, ILLINOIS, A CORPORATION OF ILLINOIS.

EXPLOSIVE ENGINE.

Application filed November 14, 1921. Serial No. 515,174.

To all whom it may concern:

Be it known that I, CHARLES A. ROBERTSON, a citizen of the United States, residing at Springfield, in the county of Sangamon and State of Illinois, have invented certain new and useful Improvements in Explosive Engines, of which the following is a specification.

This invention relates to internal combustion engines. It has to do particularly with engines of the four-cycle type, and resides in a new and improved construction and assembly of parts designed to secure certain advantages rendering the engine particularly adapted to general service uses.

The general purpose of the invention is the provision of an engine peculiarly adapted as a portable power generating unit which will fulfill the requirements of such a machine for general farm usage and the like. As a consequence of this general purpose, it is one of the particular objects of the invention to provide an engine which comprises a minimum number of parts, and the operation and maintenance of which are as simple as possible.

Another particular object of the invention is the provision of an internal combustion engine which is so constructed and arranged as to eliminate vibration as completely as possible and at the same time afford a unit of minimum weight.

Another particular object of the invention is the provision of a construction in which all of the operating parts are readily accessible.

Other and further objects of the invention will be pointed out hereinafter, indicated in the appended claims or obvious upon an understanding of the present disclosure. In the drawings forming a part of this specification, I show an embodiment of the invention, but it is to be understood that the same is presented here for the purpose of illustration merely, and that the structure is susceptible of variation and modification within the scope of the invention.

In the drawings,

Fig. 1 is a side view of the operating parts, frame members for the most part being omitted, the cylinder, water jacket and exhaust valve chamber being shown in vertical section, and the timing and ignition mechanisms in elevation;

Fig. 2 is a detail in the nature of a side elevation of the cylinder head;

Fig. 3 is a rear end view partly in elevation and partly in section;

Fig. 4 is a front elevation; and

Fig. 5 is a top view showing the frame, timing and throttle control mechanism, the cylinder portions and crank casing being removed.

By reference to these illustrations, it will be understood that the numeral 1 designates lateral frame members which may be formed most conveniently of channel bar sections disposed on edge. Adjacent their rearward extremities these frame members may be connected by a spacer or tie-bar 2, while the main connection between the lateral frame members is afforded by the cylinder casting. This is the hollow casting shown in elevation in Fig. 4 and in section in Fig. 1. It has the laterally extending bracket portions 4 connected to the respective frame members 1 by suitable bolts 4^a. The cylinder casting is of general rectangular form and comprises an external jacket portion 5, within which and spaced from the side and bottom walls of which, is formed a sleeve portion 6 which constitutes the cylinder proper. The space between the sleeve and the housing affords circulating space for cooling water in contact with the outer wall of the former, and a top aperture 5^a in the housing permits the introduction of the water thereinto. In the top portion of the sleeve 6 under the opening 5^a is cast a boss 6^a having a vertical channel communicating with the interior of the sleeve 6, on which boss is seated an oil pipe 7 which supports an oil cup 8 and affords a conduit for conveying oil therefrom to the cylinder. The forward end of the cylinder sleeve is closed by the cylinder head 9. This is a casting formed with a lower bracket 10 an upper bracket or shelf 11, the inlet valve housing 12, the exhaust valve housing 14 and the ignition plug seat 15.

Bolts 16 secure the cylinder head to the end wall of the housing 5. Upon the inlet valve housing 12 is mounted the carburetor 17, while the muffler 18 is mounted on the exhaust valve housing and the ignition plug 19 is mounted on the ignition plug seat 15. The inlet housing 12 affords communication between the carburetor and the interior of

the engine cylinder 6, while the exhaust valve housing 14 affords communication between the engine cylinder and the muffler 18. The shelf 11 supports the magneto 20 and the associated ignition contact mechanism 21, from which the connection 22 leads to the ignition plug 19. The arrangement is such that the cylinder 6 lies horizontally, the housing 5 affording a water chamber above it with circulating passages about it, and the cylinder head forming a support for the valve and ignition mechanism at the front end of the machine.

To the rear of the cylinder casting, the frame members 1 are provided with bearing members 24 in which are journalled the crank shaft portions 25 and 25^a in alignment. These bearing members are secured to the frame members 1 by bolts 26. On its inwardly extending portion, the crank shaft portion 25^a carries inertia disk 27, while the crank shaft portion 25 has an outwardly extending portion carrying the pulley 28, and an inwardly extending portion carrying inertia disk 29 and spur gear 30. Inertia disks 27 and 29 are joined by an eccentrically disposed crank pin 31, from which the connecting rod 32 leads to the piston 34 which travels in the cylinder sleeve 6. Above the wrist pin 35 the piston is provided with an oil channel 34^a adapted to align with the channel in the boss 6^a, while the connecting rod bearing 36 affords a drip cup 36^a disposed below the channel 34^a and connected by a channel 36^b with the bore of the bearing member. The inertia disks 27 and 29 are formed with the counter-balancing portions B diametrically opposite the crank pin 31, the same being of proper weight to counter-balance the weight of the connecting rod and crank pin.

The timing mechanism includes the timing gear 37 which is carried on a sleeve 38 journalled on a post 39 which is mounted on one of the frame members 1. The sleeve 38 carries a timing cam 40 and a disk 41 spaced therefrom. A timing lever 42 is pinned to a stub shaft 44 which is journalled in the lower bracket 10 of the cylinder head, one arm extending upwardly into association with the ignition mechanism, and the other extending downwardly and supporting one end of the tappet rod 45. A spring 46 tends to swing the lower end of the timing lever rearwardly. The stub shaft 44 carries a tappet arm 47 supporting an adjustable contact member 48 disposed for cooperation with the outer extremity of the stem of the exhaust valve 49, which valve is normally maintained seated by its spring 50. The rearward end of the tappet rod 45 is formed with a bifurcation 45^a which rides on the sleeve 38 between the cam 40 and the disk 41, and adjacent said bifurcation carries the roller 51 which is arranged for cooperation

with the cam 40 under the influence of the spring 46. The ratio of the gear 30 to the timing gear 37 is as 1 to 2, and the form of the cam 40 is such that the tappet rod 45 is reciprocated once at each rotation of the timing gear. The upper arm of the ignition lever 42 carries a shoe 52 which is pivoted at 54 and designed for cooperation with the operating lever 21^a of the ignition mechanism, so that upon forward movement of the upper arm of the ignition lever the dog will be rocked against the influence of its spring, the dog thereby escaping under the roller of the lever 21^a; while upon rearward movement, the rear end of the dog engages the lever 21^a and rocks it rearwardly to the point where the roller escapes from the end of the dog, whereupon the lever is swung forwardly by its spring. This operation accomplishes the energization of the ignition plug to produce a spark in the customary fashion. The form of the timing cam 40 is such that the spark mechanism is operated at the proper time, viz, at the start of the power stroke of the piston, while the relationship of the contact member 48 to the stem of the valve 49 is such that the valve is opened at the end of the power stroke of the piston, and is held open by the cam 40 during the exhaust stroke.

In the operation of the engine, therefore, the operation of the ignition lever 42 by cam 40 fires the charge, the tappet arm 47 opens the exhaust valve at the end of the power stroke, and permits it to close under the influence of the spring 50 at the end of the exhaust stroke, at which time the cam 40 has permitted the tappet rod 45 to move rearwardly, swinging the contact member 48 away from the valve stem and the shoe 52 to a position in front of the lever 21^a. At the next stroke, which is the charging stroke, the exhaust valve is held seated by its spring 50, which spring is superior to the controlling spring of the inlet valve. The latter consequently is unseated by the suction, so that a charge is drawn from the carburetor into the cylinder. At the end of the charging stroke the inlet valve is seated by its spring and, the exhaust valve likewise being seated, the charge is compressed upon the return of the piston, and then fired as above described.

I provide an automatic governing mechanism for controlling the throttle. Upon a cross yoke 55, which is connected at its ends with the lateral frame members 1, is supported a bracket 56 affording a support for the governor. The latter includes the inertia elements 57 which are displaceable outwardly by centrifugal force, and the governor pinion 58 which is driven from the timing gear 37. Outward displacement of the inertia elements 57 operates to retract the rod 59 which is connected to a bell 130

crank lever 60 pivoted at 60^a upon the yoke 55. The other arm of the lever 60 is connected to a rod 61 which has operative connection with a crank 62 which controls the 5 position of the throttle valve 64, the swinging of the crank 62 rearwardly being effective to close the valve against the influence of its spring 65. Upon increase in speed of the engine, therefore, the inertia elements 57 10 will be projected, the rod 59 retracted, and the crank 62 swung rearwardly through the intermediation of lever 60 and rod 61, to close the throttle valve 64 to an extent determined by the speed at which the governor 15 is being rotated. In this manner the supply of mixture to the engine is held under continuous and accurate control.

The fuel supply is carried in a flat tank 66 which is supported on the lower flanges 20 of the frame members 1, with a filler spout 66^a projecting at the rear, the liquid fuel being fed to the carburetor through a pipe 67. The timing and controlling gears, and other parts carried by the shafts 25 and 25^a 25 are housed by a lower casing 68 and an upper casing 69. The pulley 28 is the medium through which the power is transmitted for the intended use. A ratchet connection 70 at the extremity of the shaft 25 affords 30 means for the attachment of a crank whereby the engine may be started. The engine is adapted to be mounted on a suitable running gear to facilitate its being moved from place to place. Suitable hanger brackets 71 may 35 be connected to the frame members 1, affording support for a rear axle 72, while a front hanger 74 carrying a fifth wheel bearing 74^a may provide a support for a front axle carrier 75.

40 An engine constructed as above described may be constructed very economically because it requires but very few parts, and this feature contributes also to facilitate certainty of operation and ease of maintenance. 45 Cooling is accomplished by convection through the water contained in the jacket, the casting affording a reservoir of rel-

atively large capacity facilitating cooling of the water at the surface. Lubricant conducted through the tube 7 is delivered to 50 both the bearing surface of the piston and to the connecting rod bearing insuring in a very simple fashion the proper lubrication of these parts. Other bearings may be equipped with suitable oil cups or lubricant-receiving channels. The counter-balancing of the inertia members 27 and 29 and the connection thereof with the cylinder casting through the instrumentality of the frame members 1 minimize vibration. One 55 advantage of the construction lies in the facility with which the mechanism may be disassembled. The entire valve and ignition mechanisms may be demounted as a unit by disconnecting the bolts 16 and uncoupling 60 the tappet rod 45 from the lever 42. Likewise the cylinder casting may be removed by disconnecting the bolts 4^a and the connecting rod coupling 31^a.

70 I claim:

1. In a machine of the class described, the combination of a cylinder, a valve controlling communication to the same, ignition mechanism, a rocking lever, a piston operating in the cylinder, means for actuating said lever from said piston, and members operated through the instrumentality of said lever for operating the ignition mechanism and valve.

2. In a machine of the class described, the combination of a cylinder, a piston operating therein, a cylinder head mounted to close one end of the cylinder, a bracket mounted on said cylinder head, a valve mounted on said cylinder head, ignition 75 mechanism, a rocking arm mounted on said bracket, means for actuating said arm from said piston, and means actuated by said arm for operating said valve and ignition mechanism.

90 In testimony whereof I have hereunto subscribed my name.

CHARLES A. ROBERTSON.
